(57) **CLAIM**

The ornamental design for a peripheral device connector as shown and described.

DESCRIPTION

FIG. 1 is a front right side perspective view of a peripheral device connector showing our new design;

FIG. 2 is a back left side perspective view thereof;

FIG. 3 is a front elevational view thereof;

FIG. 4 is a back elevational view thereof;

FIG. 5 is a top plan view thereof;

FIG. 6 is a bottom plan view thereof;

FIG. 7 is a right side view thereof;

FIG. 8 is a left side view thereof; and,

FIG. 9 shows a back side left perspective view of the a peripheral device connector of FIG. 1 in an alternate position with a stand thereof extended.

The dotted broken lines depict bounds of the claim and form no part of the claimed design. The evenly dashed broken lines depict portions of the a peripheral device connector that form no part of the claimed design.

1 Claim, 7 Drawing Sheets

Related U.S. Application Data

continuation of application No. 29/747,773, filed on Aug. 25, 2020, now Pat. No. Des. 941,395, which is a division of application No. 29/645,459, filed on Apr. 26, 2018, now Pat. No. Des. 897,437, which is a division of application No. 29/595,213, filed on Feb. 27, 2017, now Pat. No. Des. 819,696.
